Fig. 5.

FIG. 1 is a top plan view of a tumbler, showing our new design;

FIG. 2 is a bottom plan view;

FIG. 3 is an elevational view;

FIG. 4 is an enlarged, fragmentary, sectional view; and FIG. 5 is a view taken on line 5—5 of FIG. 4.

The characteristic feature of our design resides in the combination, on a tumbler of the configuration shown, of the stepped indentations on the lower portion thereof and the configuration and appearance of the stacking members in the arrangement shown.

We claim:

The ornamental design for a tumbler, as shown and described.
